UNITED STATES PATENT OFFICE.

EDWARD L. ZIHLMANN, OF HUNTINGTON, WEST VIRGINIA.

HOT STOVE FOR GLASSWARE.

1,257,441.

Specification of Letters Patent. Patented Feb. 26, 1918.

Application filed July 9, 1917. Serial No. 179,497.

To all whom it may concern:

Be it known that I, EDWARD L. ZIHLMANN, a citizen of the United States, residing at Huntington, in the county of Cabell and State of West Virginia, have invented certain new and useful Improvements in Hot Stoves for Glassware, of which the following is a specification, reference being had to the accompanying drawings.

10 This invention relates to glass making appliances, and particularly to an assembly or hot stove wherein glassware, after being blown, is disposed until a certain number of pieces have been made, the completed pieces being then carried to the leer or annealing oven.

In the making of small glassware, such as tumblers, milk bottles, and like articles, it is customary to employ young boys for 20 the purpose of "cracking off" and "carrying in". The last named boys carried the ware from the shop to the annealing oven as fast as a load accumulated. The child labor law interfered with this practice and it became necessary to provide means for eliminating or at least reducing to a very large extent the number of boys employed as "carry in" boys.

The general object of this invention is to 30 provide an oven or heater wherein the glassware may be disposed while a load is being accumulated and in this connection to provide for a ready placing of the glassware within the oven or heater and a ready removal of the load therefrom.

A further object is to provide carrier pans 40 adapted to be disposed one after another within the heater and removed one after another therefrom, these pans being so constructed that the separate glass articles are kept separated from each other so as to prevent the articles which are at red heat from sticking together and eliminate loss by "melts".

45 A further object in this connection is to reduce loss due to breakage of the articles, prevent scratching and also prevent leer melts, due to an improper condition of the articles when they were taken from the heater.

A further object is to provide a heater and carrier pan therefor, so constructed that the heat can circulate freely through the 55 pans to all parts and corners thereof so that the annealing of the glass begins in the hot

stove or heater during the accumulation of the ware at the shops.

A further object is to provide means for very readily shifting the pans one by one through the stove or heater and provide for an automatic movement of the filled pan upon tracks toward the outlet door of the heater and upon said door when the latter is turned down, so as to place the filled pan in convenient position to be removed by the workman who carries the pan to the annealing oven.

Other objects will appear in the course of the following description.

My invention is illustrated in the accompanying drawings, wherein:—

Fig. 1 is a side elevation of a hot stove constructed in accordance with my invention;

Fig. 2 is a longitudinal vertical section therethrough;

Fig. 3 is a section on the line 3—3 of Fig. 2;

Fig. 4 is an end elevation of the construction illustrated in Fig. 1 looking toward the entrance end; and

Fig. 5 is a fragmentary top plan view of the hood and adjacent portions of the casing.

The stove or heater comprises a sheet iron casing approximately rectangular in cross section, the casing being designated 10. This casing is about 60" long, about 18" wide and 20" high. The middle portion of the bottom of the casing is flat and horizontal as at 11 and the bottom of the casing at its ends extends upward and outward as at 12 and 13. Each of these bottom portions 12 and 13 is provided with a cleaning opening normally closed by a slide 14. Above the middle portion of the casing there is disposed a hood 15 also of sheet metal, this hood having an opening 16 communicating with the interior of the heater and being provided with a transversely extending shelf 17 disposed above the opening. Just forward of the opening 16, the top of the heater is formed with a hinged section 18 adapted to be shifted to different angular positions, so that the free edge may be adjusted to different heights and remain in adjusted position to permit articles of different heights or sizes to be passed through the opening 16 and, of course, to accommodate pans of different heights passing along with

the chain 28. The entrance end of the heater is closed by a door 19, which is hinged to the bottom wall of the heater casing and swings upward and is held closed by a latch 20. The opposite end of the heater casing is normally closed by means of a door 21, also hinged at its lower edge to the bottom of the casing and normally held closed by means of a latch 22. The heater casing is mounted upon legs 23 whereby the casing is supported so that its end openings are approximately about waist high.

It is to be noted that the hood at one end is about 5" wide while at the other end it is 10" wide, this larger end wall protecting the hot glass from drafts of cold air. The narrow end of the hood is disposed toward the glass furnace so as to facilitate the placing of the articles of glassware onto the shelf 17. The hood is entirely open in front and the shelf 17 is about 5" wide. A hot plate 17^a is disposed upon this shelf, and rearward of the plate, the shelf is formed with openings so that heat may circulate behind the ware.

Disposed within the lower portion of the casing is a gas pipe 24 constituting a burner and provided with perforations, one end of this pipe being capped as at 25 and the other end extending to a suitable source of gas. It will be seen that this gas pipe extends longitudinally along the entire middle portion of the heater.

Disposed within the heater casing are 35 the pairs of sprocket wheels 26 and 27, upon which are mounted the sprocket chains 28. The upper flight of each sprocket chain passes over a rail 29, angular in cross section to provide an upwardly extending 40 flange spaced outward from the outer edge of the corresponding sprocket chain. These rails are supported upon supporting cross bars 30 riveted or otherwise attached to the walls of the heater. The sprocket wheels 45 27 are disposed relatively close to the entrance opening for the heater but the sprocket wheels 26 are disposed some distance from the outlet end of the heater and extending from the adjacent cross bar 30 50 are two pairs of supporting bars 31 carrying rollers 32. These supporting bars are inclined downward and toward the bottom of the exit opening and mounted upon the inner face of the door 21 are two pairs of supporting bars 31^a having rollers, these bars 55 being formed at their ends with stops 33. It will thus be seen that the rails 31^a constitute extensions of the bars 31 and that as these bars 31 are on an inclination, a carrier passing off from the sprocket chains 28 60 will run onto the rails and rest upon the rollers 32 and will roll down against the door 21 when the latter is in its raised position. When this door 21 is lowered to its 65 discharge position, the carrier will roll onto

the door and roll downward until it is stopped by the stops 33.

The shaft 34 of the sprocket wheel 27 is extended through a side wall of the casing and carries a spoked wheel 35 or other means whereby the shaft may be turned so as to shift the carrier sprocket chains. The door 21, in order to hold it supported in its lowered position, has attached to its face the U-shaped brace 36, which extends down below the lower edge of the door and is angularly bent as illustrated in Fig. 1, so that when the door is fully opened, this door rests against the inclined bottom portion 13 and holds the door in proper position to discharge the article carrier or pan.

The receptacle or pan, which is designated 37, is formed of sheet metal and is divided into compartments by intersecting partitions 38, also of sheet metal. The size of the pan and of the compartments, of course, depends upon the articles to be treated and these pans will be made of various sizes.

In operation, the tumblers, bottles or other glass articles, as they are cracked off from the blow pipe by the "crack off" boy are disposed initially upon the shelf or heated plate 17, within the hood. This insures a perfectly flat bottom for the article, as the article is red hot when placed on this plate. When a second tumbler is removed from the blow pipe and disposed on the plate 17, the first tumbler is placed into the pan 37, by passing it through the opening 16, the pan being immediately below this opening. There are three pans within the stove or heater: one is the filled pan ready to be discharged, one a hot empty pan just rearward of the filled pan and into which the articles are placed, and an unfilled pan preparatory to being moved up beneath the hinged section of the door 18. When it is desired to remove the filled pan, the door at the discharge end is opened and the pan rolls out onto the door upon the rollers 32. The operator then lifts this pan by means of tongs and carries it to the annealing oven. As fast as a pan is removed and the several pans advanced within the oven or heater, a new pan is put in position through the front door. The pans are advanced by rotating the wheel 35 which rotates the endless carrier formed by the sprocket chains 28. The burner, of course, is regulated so as to give an even temperature to the heater at all 110 times.

I have found that by the use of this pan not only is the labor greatly reduced so that one "carry in" boy is able to handle the article from four "shops" instead of one boy for each shop, but I have further found that jamming is impossible, as the partitions in the pans separate the articles from each other, thereby also eliminating any "melts." There is nothing to scratch or deface the 130

ware in any way and breakage has been reduced to about 1%.

While I have illustrated a construction which has been in practical use for some time and which is thoroughly effective for the purpose, it will be understood that the details of construction may be varied in many ways without departing from the spirit of this invention.

Having described my invention, what I claim is:—

1. A hot stove for glassware comprising a sheet metal casing open at opposite ends, means disposed within the casing whereby to maintain heat therein, doors normally closing opposite ends of the casing, a conveyer disposed within the casing having means exterior thereto whereby it may be operated, said casing having a receiving opening in its top intermediate its ends, and a section hinged to one wall of the opening and adjustable into different angular relations.

2. A hot stove for glassware comprising a sheet metal casing open at opposite ends, means disposed within the casing to maintain heat therein, doors normally closing opposite ends of the casing, said casing having a receiving opening in its top extending transversely across the casing, and a hinged section forward of the receiving opening and adjustable into a plurality of angular relations and said casing having a hood extending upward from the top wall above said opening, and a shelf disposed within 35 the hood.

3. A hot stove for glassware comprising an elongated sheet metal casing open at its opposite ends, doors hinged at opposite ends of the casing, a hood extending upward from the middle portion of the casing and opening into the interior thereof and provided with a shelf, the top wall of the casing just forward of the hood being formed with a hinged depressible section, sprocket 40 wheels mounted within the casing, sprocket chains traveling over the sprocket wheels and beneath the opening in the top, and means on the exterior of the casing for driving said sprocket wheels from time to time.

4. A hot stove for glassware comprising an elongated sheet metal casing open at its opposite ends, hinged doors normally closing the opposite ends of the casing, the top of the casing having an opening to permit 45 the insertion of the ware, a hinged section forward of said opening mounted for angular adjustment, a pair of sprocket wheels disposed at the entrance end of the casing, a pair of sprocket wheels disposed in spaced 50 relation to the exit end of the casing, sprocket chains passing over the sprocket wheels, tracks supporting the sprocket chains, bars extending from the terminus of the upper flight of the sprocket chains to 55 the rear door opening, said doors being in-

clined downward and rearward and having rollers, and means on the exterior of the casing for rotating said sprocket wheels from time to time.

5. A hot stove for glassware comprising an elongated casing having an entrance opening at one end and an exit opening at the other end, doors closing said opening, the exit door being hinged at the lower edge of the opening, means for supporting the door when it is open, means for maintaining heat within the casing, a pair of sprocket wheels disposed within the casing and adjacent the entrance end thereof, a pair of sprocket wheels disposed within the casing but in spaced relation to the exit end thereof, tracks extending between the sprocket wheels, sprocket chains mounted on the sprocket wheels and moving over the tracks and forming an endless carrier, bars extending downward and rearward from the rear ends of the tracks to a point adjacent the hinge of the rear door, said bars having rollers, and bars mounted upon the rear door in alignment with the first named bars and having rollers.

6. A hot stove for glassware comprising an elongated casing having an entrance opening and an exit opening, doors hinged at their lower edges and normally closing 50 said openings, an endless carrier extending through the casing from the forward end thereof nearly to the rear end thereof, means on the exterior of the stove for operating said endless carrier, means for maintaining heat within the casing, means receiving articles from the endless carrier and carrying said articles by gravity to the exit end of the casing, and a hood mounted upon the casing and having an opening thereto, 55 the hood being provided with a shelf on a level with the top of the casing and extending partly over said opening.

7. A hot stove for glassware comprising an elongated casing having an entrance opening and an exit opening at the ends of the casing, doors normally closing said openings, one of said doors being hinged at its lower edge and adapted to be turned to a horizontal position, the wall of the casing 60 having an opening for the insertion of the glassware, an endless carrier extending through the casing from the forward end thereof nearly to the rear end thereof, said carrier being disposed below said last-named opening, means on the exterior of the stove for operating said endless carrier, means for maintaining heat within the casing, and means receiving articles from the endless carrier and carrying said articles by gravity 65 to the exit end of the casing and to the lower edge of said last named doors.

8. A hot stove for glassware comprising an elongated casing having a door at one end hinged at its lower edge and opening 70

25
downward to a downwardly and outwardly inclined position and provided with parallel tracks upon its inner surface, said casing having an opening for the insertion of the glassware disposed intermediate the ends of the casing, an endless carrier extending through the casing nearly to the rear end thereof and disposed below the last named opening, means for operating said endless carrier, means for maintaining heat within the casing, and tracks receiving articles from the endless carrier and discharging articles upon the tracks on the door, and downwardly and rearwardly inclined, whereby to cause said articles to move by gravity to the exit end of the casing.

9. A hot stove comprising an elongated casing having doors at its forward and rear ends, means for maintaining heat within

the interior of the stove, an endless carrier 20 mounted within the stove and adapted to carry articles to the exit end thereof, the top of the stove being formed with an opening for the insertion of articles, and an article receptacle adapted to rest upon the 25 endless carrier formed of sheet metal and having sheet metal partitions defining compartments within which the articles can be placed, the partitions separating the articles from each other to thereby prevent the articles from sticking together and scratching.

In testimony whereof I hereunto affix my signature in the presence of two witnesses.

EDWARD L. ZIHLMANN.
